CLAIM

The ornamental design for a connector as shown and described.

DESCRIPTION

FIG. 1 is a perspective view of a connector according to the new design

FIG. 2 is a right side view thereof;

FIG. 3 is a left side view thereof;

FIG. 4 is a front side view thereof;

FIG. 5 is a back side view thereof;

FIG. 6 is a top side view thereof; and,

FIG. 7 is a bottom side view thereof.

The ornamental design which is claimed is shown in solid lines in the drawings. The broken lines in the drawings show portions that form no part of the claimed design.
